UNITED STATES PATENT OFFICE.

ERNEST GAUTHIER, OF CHICAGO, ILLINOIS, ASSIGNOR TO WESTERN ELECTRIC COMPANY, INCORPORATED, OF NEW YORK, N. Y., A CORPORATION OF NEW YORK.

CRANK-SHAFT.

Specification of Letters Patent. Patented Mar. 12, 1918.

1,258,761.

Application filed July 20, 1917. Serial No. 181,787.

To all whom it may concern:

Be it known that I, ERNEST GAUTHIER, a citizen of the United States, residing at Chicago, in the county of Cook and State of Illinois, have invented certain new and useful Improvements in Crank-Shafts, of which the following is a full, clear, concise, and exact description.

This invention relates to a crank-shaft, and more particularly to an adjustable crank-shaft which is especially applicable for use with open back inclinable presses in which it is desirable to vary the length of the stroke of the press.

Adjustable crank-shafts have been and are in common use with presses in which the shaft is supported by a single bearing surface. When the shaft is supported by a double bearing, between which the crank and its associated pitman reciprocate, however, serious difficulties are encountered in producing satisfactory adjustable crank-shafts.

It is one of the objects of this invention to provide an improved adjustable crank-shaft in which the crank is supported on either side by a bearing surface.

Another object consists in an improved adjustable crank-shaft construction whereby the strength of the shaft against shearing and torsional strains is materially increased and whereby adjustability is obtained with a minimum number of parts.

A further object consists in simplified means for varying the throw of the crank and for accurately determining the amount of said throw.

Other objects of the invention will become apparent from the following description and the appended claims.

In the preferred form of the invention herein described it has been applied to an open back inclinable press, but it will be quite obvious that the improved adjustable crank-shaft may be applied to numerous other devices and machines, such as heading machines and the like, and that consequently the invention is not limited to this preferred application, the scope thereof being limited only by the claims.

In the operation of presses it is very desirable to vary the stroke of the movable die, the most efficient stroke depending upon the character of the work which is to be performed. Thus it is advisable to limit the stroke of the press so that the movable die

will not move through a distance very much greater than the thickness of the material which is being operated upon. By thus limiting the stroke of the press, two distinct advantages are obtained. First, the necessity of tool guards is eliminated, as the die does not recede a sufficient distance from the article operated upon to permit the interjection by the operator of his hands or fingers between the die and the material; second, by shortening the stroke so that its length will be just sufficient to clear the article operated upon, the speed of operation can be greatly increased and likewise the shearing operation between the die and material operated upon will be more efficiently performed.

For these reasons an adjustable crank-shaft which can be used with open back inclinable presses and in which the crank is supported on either side by a bearing surface is very desirable, since it protects the operator and also increases the speed and efficiency of operation.

The invention is illustrated in the accompanying drawings, in which:

Figure 1 represents a perspective view of the improved crank-shaft;

Fig. 2 is an end elevation thereof;

Fig. 3 shows the shaft dismantled with the parts in their relative positions;

Fig. 4 is a section on the plane 4-4 of Fig. 2.

Fig. 5 shows the locking key;

Fig. 6 is a developed view of the calibrations on the outer peripheral surface of the adjustable eccentric and the collar;

Fig. 7 shows the spiral locking spring;

Fig. 8 illustrates a perspective view of an open back inclinable press equipped with the improved adjustable crank-shaft.

As illustrated in Figs. 1 and 3, the shaft comprises the bearing surfaces 10 and 11 and the integral eccentric 12 and collar 13. Fitted on the eccentric 12 is the adjustable eccentric 14, integral with which are the calibrated flanges 15 and 16. The adjustable eccentric 14 is designed to fit on the eccentric 12 integral with the shaft and is of such a length that it can be nicely fitted on the eccentric 12 between the integral collar 13 and the removable collar 17. The removable collar 17 is secured to the eccentric 12 by means of keys which fit in the key-ways 18 and 19 of the collar 17 and the co-operating

key-ways such as 20 in the eccentric 12. When the adjustable eccentric 14 is fitted in place on the eccentric 12 integral with the shaft 11 between the collars 13 and 17, it can 5 readily be rotated about said eccentric 12, the relative position of these two eccentric surfaces determining the throw of the crank.

Loosely journaled on the outer surface of the adjustable eccentric 14 between the 10 flanges 15 and 16 is the pitman or upper connection 24. The bearing surface of the pitman 24 fits between the flanges 15 and 16. This bearing surface is composed of two 15 parts, the lower half being connected to the pitman, and the upper half being connected to the lower half of the bearing surface by the bolts 25 and 26. The coöperating bearing surfaces of the pitman and the adjustable eccentric 14 may be lubricated in any 20 desirable manner, preferably through an oil hole such as 27.

The outer peripheral surface of the flanges of the adjustable eccentric 14 is fitted with a series of circumferential notches 25 or key-ways such as 22 suitably calibrated for six different positions of the adjustable eccentric. The collars 13 and 17 are fitted with similar key-ways and like calibrations. The adjustable eccentric 14 is secured to the 30 shaft by means of the collars 13 and 17 through the agency of keys such as 28, illustrated in Fig. 5, which are driven into the coöperating key-ways such as 22 of the adjustable eccentric 14 and the collars 13 and 17 after the adjustable eccentric has been moved so as to place said key-ways in proper alignment. The key-ways in these collars and the adjustable eccentric 14 are so placed that for any given throw of the crank, two 40 of said key-ways on each collar will be in alignment with two similar key-ways on the adjustable eccentric.

Each of the keys 28 is fitted with a groove 45 30, said groove serving to receive a stiff spiral spring 31, illustrated in Fig. 7. The collars 13 and 17 are fitted with similar grooves 32 and 33 respectively. When the adjustable eccentric 14 has been rotated and adjusted to give the desired throw, and the 50 keys 28 placed in position in the coöperating key-ways of the collars and the adjustable eccentric, the springs such as 31 are snapped into position in the grooves 32 and 33 in the collars 13 and 17. One end of the spring 31 is fitted with a right angled projection 34 which fits in a suitable slot such as 35 provided in each of these collars, one of which is illustrated in Fig. 2.

As hereinbefore stated, the outer peripheral surfaces of the collars 13 and 17 and of the flanges of the movable eccentric 14 are calibrated to indicate the throw of the crank. These calibrations are placed on these collars and on the flanges so that when 65 the numerals representing the same amount

of throw on the collar and on the flange are in alinement, one of the circumferential notches or key-ways in each collar will be in alinement with a similar key-way in each flange of the adjustable eccentric. As illustrated in the developed view in Fig. 6, these 70 collars and flanges are adjustable for six different lengths of throw—namely, $\frac{1}{4}$, $\frac{3}{8}$, $\frac{1}{2}$, and $\frac{3}{4}$ of an inch and $1\frac{1}{8}$ and $1\frac{1}{2}$ inches. Obviously the calibrations and the key-ways 75 cut in the flanges and collars respectively can be readily altered to obtain any desired amount of throw and hence any desired amount of variation in the length of stroke between two successive steps may be readily 80 obtained. In the calibration here shown the increasing increment for the shorter strokes is one-eighth of an inch, varying from one-quarter to three-eighths and then to one-half an inch. The stroke then increases by one-quarter of an inch, increasing from one-half to three-quarters of an inch, the remaining steps being three-eighths of 85 an inch, increasing from three-quarters to one and one-eighth and then to one and one-half inches. These particular stroke lengths have been chosen since they most satisfactorily meet varying operating conditions. The method of calibration and the position of the key-ways are clearly illustrated in 90 Fig. 6, in which figure the adjustable eccentric is shown in a position for a quarter inch stroke of the crank.

Fig. 8 shows the adjustable crank-shaft in position on an open back inclinable press and suitably journaled in the bearings 40 and 41. As here shown, the pitman 24 is connected to the reciprocating slide of the press 42, to which the punch is attached by means of the screws 44 and 45. A suitable 105 die is secured to the base 46 of the press. When the crank-shaft has been thus mounted, the desired movement of the reciprocating slide is obtained by changing the position of the movable eccentric 14 with respect to the eccentric 12 integral with the shaft 11. In adjusting the crank-shaft, it is first necessary to remove the retaining spring 31, which can be readily accomplished by prying the spring out of the slot by any suitable tool. 115 The keys 28 are then removed, after which the adjustable or movable eccentric 14 may be rotated, thereby changing its relative position to the collars 13 and 17 and likewise its relative position to the eccentric 12, which 120 will vary the amount of throw. This movement can be readily accomplished by either a spanner wrench which will fit in the circumferential notches or key-ways in the flanges of the adjustable eccentric 14, and 125 with which the adjustable eccentric may be turned, or it may be accomplished by inserting a rod in the hole 47 in the end of the shaft illustrated in Fig. 8 and moving the shaft by means of the rod so that the eccen- 130

tric 12 integral with the shaft will change its position with respect to the movable eccentric 14. In this adjustment the adjustable eccentric is moved or turned until the corresponding numbers or calibrations on the collar and flange of the movable eccentric, representing the desired amount of throw, are in alinement or opposite each other. When the corresponding numbers are thus alined, a key-way 22 in each of the collars will be in alinement with a similar key-way in each of the flanges of the adjustable eccentric and thus permit the insertion of a key such as 28 in each of these key-ways. The retaining spring 31 is then sprung into the groove, after which the shaft is ready to be used. This same operation is repeated for any length of stroke which is desired, the designation for which appears on the calibrated outer periphery of the collars and the flanges of the movable eccentric 14.

It will be observed from the foregoing description that the improved adjustable crank-shaft herein described has its greatest cross section and is consequently strongest for that portion of the shaft which contains the adjusting features and which is held between the bearings 40 and 41. Consequently the addition of the adjustable element of the shaft has not weakened it, the shaft if anything being stronger for that portion of its length which contains the adjusting elements. It will also be observed that the adjustable feature of the shaft is obtained by the use of three parts—the eccentric and collar integral with the shaft, the adjustable eccentric, and the removable collar. These parts are all held together by means of key-ways and four keys, thereby eliminating the use of many small parts, such as screws, pins, etc., which have heretofore been used with adjustable crank-shafts supported by a single bearing.

Obviously the invention is not limited to the specific embodiment herein illustrated and described, but is capable of many variations and other applications without departing from its spirit and scope, as pointed out in the appended claims.

What is claimed is:

1. In a press, in combination, a rotatable crank-shaft, bearings in which said shaft is journaled located at either side of said crank, a slide reciprocated by said crank, and means for adjusting said crank to vary the length of the stroke of said slide, said means permitting movement of said slide in both directions for all positions of said crank.
2. In a press, in combination, a rotatable crank-shaft, bearings in which said shaft is journaled located at either side of said crank, a slide reciprocated by said crank, and a pair of coöperating one-piece eccentrics which may be adjusted to vary the length

of the throw of said crank whereby the length of the stroke of said slide will be altered.

3. In a device of the character described, in combination, a shaft, an eccentric and collar integral with said shaft, a second eccentric adjustably fitted over said first-mentioned eccentric, a removable collar, means to secure said removable collar to said first eccentric, and means to secure said adjustable eccentric to both of said collars.

4. In a device of the character described, in combination, a shaft, an eccentric integral with said shaft, a second one-piece eccentric adjustably fitted over said first-mentioned eccentric, means to hold said eccentrics in this relative position, and means to rigidly connect said second eccentric to said shaft.

5. In a device of the character described, in combination, a rotatable shaft, an eccentric, a second one-piece eccentric adjustably fitted over said first-mentioned eccentric, means to retain said eccentrics in this position, means to secure said second eccentric to said shaft, and a pitman journaled to said second eccentric and reciprocated thereby as the shaft is rotated.

6. In a device of the character described, in combination, a shaft, an eccentric and collar integral therewith, a second eccentric adjustably fitted over said first-mentioned eccentric, a removable collar, means to secure said removable collar to said first-mentioned eccentric, means to secure said adjustable eccentric to both of said collars, and a pitman journaled to said second eccentric and reciprocated thereby as said shaft is rotated.

7. In a device of the character described, in combination, a shaft, an eccentric and collar integral with said shaft, an adjustable eccentric coöperating with said first-mentioned eccentric, a removable collar, means to secure said removable collar to said first-mentioned eccentric, corresponding calibrations on said collars and said second eccentric, and means whereby said second eccentric may be locked to said collars when a calibration on the adjustable eccentric is alined with like calibrations on said collars.

8. In an adjustable crank-shaft, in combination, a shaft, an eccentric and collar integral with said shaft, an adjustable eccentric coöperating with said first-mentioned eccentric, a removable collar, means to secure said removable collar to said first-mentioned eccentric and retain said adjustable eccentric in a desired position between said collars, circumferential key-ways in said collars and in said adjustable eccentric, and keys for locking said adjustable eccentric to said collars in any one of a plurality of positions.

9. In an adjustable crank-shaft, in combination, a shaft, an eccentric and collar integral with said shaft, an adjustable eccentric

coöperating with said first-mentioned eccentric, a removable collar, means to secure said removable collar to said first-mentioned eccentric and retain said adjustable eccentric in a desired position between said collars, circumferential key-ways in said collars and in said adjustable eccentric, keys for locking said adjustable eccentric to said collars in any one of a plurality of positions, and 10 silent means for retaining said keys in position in said key-ways.

10. In an adjustable crank-shaft, in combination, a rotatable shaft, an eccentric integral with said shaft, bearings in which 15 said shaft is journaled located at either side of said shaft, an adjustable one-piece eccentric coöperating with said first-mentioned eccentric, a pitman coöperating with said second eccentric, and means for changing the relative position of said two eccentrics whereby the throw of said pitman will be altered.

11. In an adjustable crank-shaft, a rotatable shaft, an eccentric integral therewith, an adjustable one-piece eccentric coöperating with said first-mentioned eccentric, retaining collars for said adjustable eccentric secured to said first eccentric, and peripheral calibrations on said collars and said adjustable eccentric to determine the amount of

throw of the crank which is controlled by the relative position of said two eccentrics.

12. In a device of the character described, in combination, a rotatable shaft, an eccentric and collar integral with said shaft, an 35 adjustable eccentric coöperating with said first-mentioned eccentric, a removable collar, a key for securing said removable collar and said second eccentric said collars serving to retain said adjustable eccentric in position, 40 flanges associated with said adjustable eccentric, key-ways in the circumferential surface of said collars and said flanges, calibrations on the circumferential surface of said collars and said flanges said calibrations, 45 when brought into proper alinement serving to aline the key-ways in said collars and said flanges, keys for securely connecting said adjustable eccentric to said collars through the agency of said alined key-ways, 50 and a pitman coöperating with said adjustable eccentric and journaled on the outer surface of said adjustable eccentric between said flanges, said pitman being reciprocated when said shaft is rotated and said reciprocation depending upon the relative position of said two eccentrics.

In witness whereof, I hereunto subscribe my name this 30th day of March, A. D. 1917.

ERNEST GAUTHIER.
